(57) **CLAIM**

The ornamental design for a portable electronic device case,
as shown and described.

DESCRIPTION

FIG. 1 is a top, front perspective view of the portable electronic device case of the instant invention;

FIG. 2 is a bottom, rear perspective view thereof;

FIG. 3 is a front view thereof;

FIG. 4 is a rear view thereof;

FIG. 5 is a right side elevational view thereof;

FIG. 6 is a left side elevational view thereof;

FIG. 7 is a top view thereof; and,

FIG. 8 is a bottom view thereof.

The broken lines shown are included for the purpose of illustrating the unclaimed portions of the article that form no part of the claimed design.
